(57) **CLAIM**

The ornamental design for a handle for a storage bucket, as shown and described.

DESCRIPTION

FIG. 1 is a top perspective view of a handle for a storage bucket;

FIG. 2 is a bottom perspective view thereof;

FIG. 3 is a front elevational view thereof;

FIG. 4 is a top plan view thereof;

FIG. 5 is a bottom plan view thereof;

FIG. 6 is a right side elevational view thereof;

FIG. 7 is an enlarged, top perspective view thereof; and,

FIG. 8 is an enlarged, bottom perspective view thereof.

The ornamental design which is claimed is shown in solid lines in the drawings. The broken lines in the drawings form no part of the claimed design. A rear elevational view is not shown because it is identical to the front elevational view shown in FIG. 3. A left side elevational view is not shown because it is identical to the right side elevational view shown in FIG. 6.
